UNITED STATES PATENT OFFICE.

FREDERICK C. DOLCATER, OF WASHINGTON, DISTRICT OF COLUMBIA, ASSIGNOR TO MONTAGUE MAILING MACHINERY CO., OF CHATTANOOGA, TENNESSEE, A CORPORATION OF TENNESSEE.

PRINTING APPARATUS.

1,236,153.

Specification of Letters Patent.

Patented Aug. 7, 1917.

Application filed August 5, 1914. Serial No. 955,238.

To all whom it may concern:

Be it known that I, FREDERICK C. DOLCATER, a citizen of the United States, residing at Washington, District of Columbia, have invented certain new and useful Improvements in Printing Apparatus, of which the following is a specification.

My invention relates to printing machinery of the general type in which a series of record plates bearing addresses or other information are passed through the machine, and the impressions taken therefrom, and my present invention concerns particularly means whereby certain of the record plates may be selected for printing and the others skipped in the printing. By my invention it is possible to send the whole list of plates through the machine, but to print from only certain of these plates according to the different classes in which they belong.

Another feature of my invention relates to selecting mechanism to determine the kind or color of the form which is to be fed into the machine by the attendant, the call for a blue form, for instance, being indicated by a blue flash light, for a yellow form by a yellow flash light, and a white form by a white flash light.

Another feature of my invention contemplates the selection of values, which the plates represent, and their accumulation on a register mechanism which also may be employed for printing the total of the values or numbers which the plates represent.

The invention consists in the features of construction and combination and arrangement of parts hereinafter described and particularly set forth in the appended claims.

In the accompanying drawings

Figure 1 is a side elevation of a portion of the machine embodying my invention;

Fig. 2 is a plan view of a portion of the said machine;

Fig. 3 is a detail sectional view;

Fig. 4 is a view similar to Fig. 3, but with some parts omitted and with the mechanism in a different position;

Fig. 5 is a detail view of one of the arms of the bell crank lever;

Fig. 6 is a view of the other arm of said lever;

Fig. 7 is a detail view of the shuttle bar;

Fig. 8 is a detail view of the record plate;

Figs. 9 and 10 are views respectively of the back and front sides of the record plates 55 embossed for the selection of numbers;

Fig. 11 is a plan view of the number selecting mechanism;

Fig. 12 is a sectional view of said mechanism; and

Figs. 13 and 14 are detail views.

In these drawings, 1 indicates the impression bar which is mounted to slide vertically in the frame, and is operated from a shaft 2 through arms 3 fixed on said shaft and connected by links 4 to cross bars 5 which are connected with the vertically extending rods 6, these rods being connected at their upper ends to the impression bar. The shaft 2 is rocked by an arm 7 fixed thereto having a pin 8 to be borne upon by a pawl 9, said pawl being pivotally mounted at 10 to one of the arms 11 of a bell crank lever, the other arm of which shown at 12 is loosely connected with the arm 11, and both are 70 loosely mounted on the shaft 2. The arm 11 of the bell crank lever is operated through any suitable link connection as 13 extending to a crank or other element to which power is applied in any suitable way. The arm 80 12 of the bell crank lever is utilized to operate the record plate feed mechanism, it being understood that these record plates are brought to the impression point by a step by step movement from a suitable hopper, the runway for the said plates being indicated generally at 14. This plate feed mechanism may be of various forms, and the particular form of this mechanism does not constitute a part of my invention, and I 85 have therefore shown it only generally.

This mechanism consists in a link 15 operated from an arm 16 on a shaft 17, the said shaft being operated through arm 16' from the lever arm 12 through what may be 90 termed Du-tri mechanism. This term is coined from the words, "duplicate" and "triplicate." This mechanism, under the control of the operator, may be set to regulate the plate feed for making either single, 95 duplicate, triplicate or multiple impressions from the same plate. The arm 12 has a pro-

jection 12^b which enters a channel 16^b in the arm 16' indicated in dotted lines in Fig. 1. The link 15 is connected with a bell crank lever 18 which, in turn, through a link 19, connects with a shuttle bar 20 having dogs 21 thereon for engaging the plates and feeding them forward one step at each reciprocation of the shuttle bar. The arm 12 of the bell crank lever 11—12 engages the arm 16' of the Du-tri mechanism. I refer to this Du-tri plate feeding mechanism as an example of any desired mechanism that may be used for the purpose. The arms 11 and 12 of the bell crank lever, as stated above, are each loosely mounted on the shaft 2, and they are connected by toggle links 23, 23', by which, when the arm 11 is moved in the arrow direction, the links will move the arm 12 in the same direction, and through the connections described the shuttle bar for feeding the plates will be retracted to get into position for a new feed of the plates. This same movement of the bell crank arm 11, through the pawl 9, will move the impression head down. On the reverse movement of the arm 11 the impression bar will rise and the downward movement of the arm 12 will effect the movement of the plate feed mechanism to feed the plates forward, this movement of the arm 12 being due to a spring connection between the arm 11 and the link 23, and I have shown this spring at 25, the purpose being to allow the arm 12 to yield or lag in its movement downwardly should a record plate become jammed in its guideway.

Detector mechanism.

The detector mechanism for selecting certain of the plates for printing involves a specially constructed series of record plates and mechanism to coöperate therewith to determine which of the plates shall be printed as they pass through the machine. Selective record plates heretofore have been employed, but in my system I employ the well known Montague form of one piece embossed record plates and the selecting means I emboss on the plates, and preferably I employ the characters of the alphabet or numerals or other alphabetical signs as the selecting means. I have shown, for instance, a row of selecting embossings at X on a record plate, consisting in this instance as shown in Fig. 8, of the characters A, B, C, D, F, and Z, and this will indicate that this plate belongs in a number of different classes and will be printed when the different classes to which it belongs are to be selected and printed. Coöoperating with the record plates are contact points, or only a single point may be used, this point or points being indicated at Y, and being carried removably and interchangeably in a holder 26. This holder may

be constructed in various ways, but I prefer to form it of insulating fiber having slots or openings for receiving the detector fingers Y. These detector fingers are rubber covered at their exposed portions excepting their extreme ends, which are left bare to contact with the selecting points or embossings on the record plates. The holder 26 is carried on stems 27 movable vertically through the bed of the machine at 28, and connected by a cross pin 29 against which arms 30 may bear, said arms being mounted on a rock shaft 31 suitably journaled in a bracket of the frame, and operated through an arm 32 fixed thereon and a link 33 which is connected with the arm 12 of the bell crank lever 11—12. The holder 26 is normally pressed upwardly by a spring 34. The detector consisting of the plate 26 with its detector fingers is located one step in advance of the impression point, that is to say, the record plates as they are moved step by step from their hopper to the impression point arrive first at the detector station indicated at A in the plan view, Fig. 2, and after resting here the plates are given another step to the left which brings them to the impression point. While at the station A each plate is instrumental in determining whether it will be printed upon or skipped when it arrives at the next station, *i. e.*, the impression point. It will be observed that as the bell crank lever 11—12 rises, and the impression bar descends, the arms 30, through the link and arm connection 33 and 32, will lower the detector plate and bring a detector finger into contact with any of the contact points or embossings X which may underlie the same. This will close the circuit to an electro-magnet 36 and this, through its armature 37 and rock shaft 38, will set a latch 39 from the position shown in full lines in Fig. 3 to that shown in dotted lines in said figure. The upward movement of the bell crank lever 11—12 has brought the pawl 9 to its uppermost position, and a pin 9' on said pawl now overlies the slot 40 in the latch 39, this latch having been adjusted as just stated to the dotted line position. Now when the movement of the parts is reversed and the bell crank moves downwardly or opposite the arrow direction and consequently when the impression bar is rising, the pin 9' of the pawl 9 will enter the slot 40 of the latch 39 and in the final part of the movement the pin will come against the lower edge of this slot and therefore the pawl will be tipped so that its right hand end will be thrown down below the plane of the pin 8. The parts are now in position for another cycle to begin, and it will now be seen that as the bell crank lever 11—12 rises the pawl 9 will miss the pin 8 and consequently no move-

ment will be transmitted to the shaft 2, and the impression bar or head will not be moved downwardly. When, however, the reverse movement just above described is taking place, that is, the movement of the bell crank lever 11-12 in a direction opposite to the arrow, the plate which had been resting at station A has been moved by the plate feeding mechanism from said station to the impression point below the impression bar, but as the impression bar does not move down owing to the setting of the pawl 9 in ineffective position, no impression will be made from the plate just mentioned, but on the contrary on the next cycle this plate will be moved from the impression point toward the discharge point of the machine.

A spring 9^x returns the pawl or controller 9 to normal position.

It will be observed that the record plates having the selective device embossed thereon are of advantage over any form of plate having removable tabs or other adjustable selective means. The plate can be made of a selective character at the same time that the address or information is embossed thereon, that is, while the plate is in the machine being embossed with the address it can be embossed at the same time and by the same machine with the character or characters which are to classify the plate.

Furthermore, it happens that a customer must be transferred from one class to another. To do this, it is simply necessary with my invention to blank out, *i. e.*, press down or obliterate the selector character and reemboss the plate with the selector character at the proper point to put the customer in his proper class. With the embossed selector devices danger of loss of identity of the plate is prevented.

By employing alphabetical characters or numbers as the selective devices, the class or classes to which the plate belongs can be read at a glance. For instance, if the letter *a* appears as the selective character, the plate belongs to the *a* or first class. If *c* appears it can be seen that it belongs in the third or *c* class. Each class, therefore, will be designated by its own particular sign or combination of signs which will be different from the signs or combination of signs designating other classes. These signs will not only be distinctive in themselves, but their location will be distinctive; thus *a* will occupy the first position; *d* the fourth, and so on throughout the list of signs, so that the operator, in embossing the plate, will be able to place the sign in proper position quickly and certainly, and the liability of mistake will be reduced.

Furthermore, the embossed classifying sign can be printed on the wrapper, envelop, card or other matter, because the said

sign is raised from the main body of the plate just as the letters or characters of the address or other information is raised or embossed. By reason of this the article when printed will have a class indication thereon by which it may be identified and treated differently and separately as may be desired from all printed articles belonging to other classes.

As above stated, the record plate is of the type known as the Montague manufactured under patents of Owens, 939,739, November 9, 1909, and Lee, 982,076, January 17, 1911.

The plate has a main portion with embossed characters thereon, and it has margins offset to one side of the plane of the plate by which the plate is guided. The main portion of the plate is elevated and the printing characters are thus brought to the proper plane.

The selecting embossings are made in this raised or main part of the plate. These embossings are made preferably near one edge of the plate, and it will be noticed that the detector plate is so located that its fingers will extend over the guideway in the table and over the depressed rolled margin of the plate into position to contact with the selective embossings on the plate. The plate feeder is arranged below the surface of the table and in position to engage one of the depressed margins of the plate.

Reverting to the latch 39, of course it will be understood that when a plate comes along that is to be printed the latch 39 will remain in its normal position shown in full lines, because the circuit will not be closed, due to the absence of a selector embossing, and the magnet will not be energized.

The latch 39 is returned to normal position by a spring 40^x. In the arrangement described the plates with the selector embossings will be skipped in the printing, but the arrangement may be such that the embossings X will be placed on those plates which are to be printed. This may be done by arranging the spring 40^x to move the latch 39 to the dotted line position while the magnet will pull the latch into the full line position. The arm 11 has a lug 11^x to engage the pin 8 and raise the impression head.

Selecting and accumulating number items.

In certain classes of work, for instance where a number of checks are being printed, it is desirable to register the values that the plates represent on accumulator mechanism, so that when the list of plates has been run through the machine, the total will appear, and an imprint of this total may be made either on a separate slip or on the record strip or sheet which has just received thereon the list of items.

Referring to Figs. 9 to 13, the record plates are adapted to receive embossing X' at or near one end thereof, representing numbers of the desired denominations.

5 The spaces for receiving the embossings are indicated by the lines X² shown in Fig. 9 impressed in the back of the plate when it is formed. I show as an example five columns representing units, tens, hundreds, etc., and each column having nine spaces representing digits running from 1 to 9. I have indicated the position of these digits by the numbers 1 to 9. Supposing the plate is to represent a value of one hundred 10 and eighty-six dollars and twenty-five cents, the embossings would appear in the positions indicated in Figs. 9 and 10. Coöperating with such a plate I employ a contact head having as shown in Figs. 12, 13 and 15 20 14 a fiber body 26' supported on fiber posts as before described and pressed up by springs, as indicated. In this fiber plate a series of contacts 42^x are mounted. These consist of pins having enlarged heads 44 25 and nuts or collars 45 screwed on their lower ends. A spring 46 presses each pin normally downward, this spring resting against the contact plate 47 fixed in the opening in the fiber plate, and against the lower collar or 30 nut 45. The pin 42^x is held by the spring with its lower end and the face of the collar or nut about flush with the lower face of the fiber contact head, the head 44 of the pin acting as a stop to limit the downward movement of the pin. There is a row of these 35 pins for each order of digits, units, tens, hundreds, etc., and each row contains nine pins representing digits from 1 to 9 inclusive. Coöperating with these pins there is 40 a series of slides 48, one slide for each order of digits. In the example shown there are five rows of digits, and consequently there are five slides 48. These are adapted to move in ways formed in the fiber plate and 45 just above the plane of the upper ends of the pins when these are in normal position. The slides are confined in their grooves by a glass plate 49 fixed to the fiber plate. Each of these slides has a rack 50 connected with an 50 item wheel 51, there being one such wheel for each slide, and the connection may be made in various ways. In the particular construction shown this connection is made through a gear wheel 52 carrying a pawl 53 55 engaging a ratchet wheel 54 connected with the number wheel.

The slides are moved to the right, Fig. 12, or in the direction of the arrow, Fig. 11, to be set up in positions corresponding to the 60 values of the digits which are selected. Fig. 11 shows the slides in set up position resting against the stops 44 which have been elevated by coming in contact with the embossed points on the record plate, this being 65 due to the depression of the head carrying

all the pins. Only those pins will be raised which come in contact with the embossed points. The slides 48 are moved to set-up position by electro-magnets 54 which, when energized, draw armatures, one of which is 70 shown at 55. The armatures are carried by levers, one for each slide connected thereto at 57. The levers are slotted and pivoted at 58, the slot allowing the levers to rise and fall as the contact head moves up 75 and down. The magnet is energized through suitable circuit connections by the contact pins of the contact head coming against the embossed selecting points on the plate, and the slides will thus be moved to different degrees 80 according to the position of the stop pins raised in the contact head. On the movement of the slides to set-up position shown in Fig. 11, no movement of the number wheels takes place. For restoring the 85 slides to normal position and thereby transferring their values to the number wheels, the levers 56 are provided with arms 59 overlying a pin 60 carried by the cross bar 61 of the impression frame, so that when 90 the impression frame rises the slides will be moved and the number wheels will be turned according to the values of the digits to be added.

Any sort of carrying mechanism common 95 in adding machines may be employed for carrying tens from one order to the next higher order and any sort of accumulator mechanism may be used, such not forming a part of my invention excepting in a broad 100 sense.

The mechanism just described for selecting numbers may be employed in the same organization with the means for selecting and printing only certain of the plates. 105

The counting wheels may be located either at the front or rear of the runway.

In respect to the circuits in Figs. 11 to 14, each series of contacts 44 will be connected up with a magnet 54 before mentioned, there being one of these magnets for each order of digits which it is desired to count. The stop and contact pins 44 of each order are connected together electrically in any suitable manner, as by making 110 the seat 47 in the form of a strip in which all the stops of one order are seated, this strip being in circuit with the magnet, but there is a separate circuit for each order of digits. When any one of the contacts 44 of 115 either order of digits contacts with the selector embossing on the record plate, the magnet will be energized and the slide 48 will be moved until it is arrested by the elevated contact stop 44.

The circuit wires are indicated diagrammatically in Figs. 12, 13 and 14 at x and y.

It will be clear that the mechanism of Figs. 1 to 8 for controlling the impressions from detector mechanisms of which the 120

plate forms a part and the counting mechanism of Figs. 9 to 14 of which the printing plate also forms a part are to be used in the same machine, it being obvious that the 5 detector or contact mechanism will be disposed along the runway at different points.

The printing plate *per se* is not claimed herein as this has been made the subject matter of application #145,480, filed January 10, 1917.

I claim as my invention:—

1. In a printing apparatus, a table having runways below the surface thereof, an impression member operating to and from 15 the table, and printing plates having a main portion exposed between the runways and with depressed margins in the runways, said plates having printing characters embossed from their exposed main portions and having 20 selector embossings also raised from said exposed main portions, and detector means coöperating with the selector embossings, substantially as described.

2. In combination in a printing apparatus, a series of record plates each having a raised main portion and depressed margins, a guideway receiving the depressed margins, said record plates having embossed printing characters and selectors extending 30 up from said plate thereon, and detector means having detector fingers reaching across the depressed margin of the plate and over the main body of the plate to engage only the projecting selector with 35 means for operating the detector means, substantially as described.

3. In combination in a printing apparatus, a series of record plates each having a raised main portion and depressed margins, 40 a guideway receiving the depressed margins, said record plates having embossed printing characters and embossed selectors thereon, and detector means consisting of a holder having detector fingers reaching 45 across the depressed margin of the plate and over the main body of the plate to engage the embossed selector with means for operating the holder, said holder being located to one side of the path of the record 50 plates and having movement vertically, substantially as described.

4. In combination in printing apparatus, an impression head, a series of record plates, some of which have selecting means thereon, 55 a rocking arm, means for rocking the arm, a shifting controller or pawl carried thereby, a rock shaft, a connection from said rock shaft to the impression head, means on the rock shaft to be engaged or disengaged 60 by the controller, and means controlled by the selector means on the record plate to set the controller in position to cause said head to make or miss an impression, substantially as described.

5. In combination in a printing appara-

tus, a series of record plates some having selecting means, a rock shaft, an arm loosely mounted on the rock shaft, means for oscillating the arm, a pawl pivoted to the arm, said pawl engaging with or disengaging 70 from a part on said rock shaft, an impression head, connections from the rock shaft for operating the impression head, a latch for shifting and holding the pawl, and connections controlled by the selector means 75 on the record plate for operating the latch, substantially as described.

6. In combination an impression head, a two armed lever, a shiftable controller mounted on said lever, connections controlled by the controller for moving the impression head, record plates some having selector means, a detector coöperating with said selector means to determine the making of impressions through the controller, and a 80 connection for operating the detector from the two-armed lever, substantially as described.

7. In combination an impression head, a two-armed lever, a shiftable controller 90 mounted on said lever, connections controlled by the controller for moving the impression head, record plates some having selector means, a detector coöperating with said selector means to determine the making 95 of impressions through the controller, a connection for operating the detector from the two-armed lever, a plate feeder operated from said two-armed lever, and a yielding connection between the arms of the lever to 100 yield on failure of the plates to feed, substantially as described.

8. In combination impression means, a table having a straight runway, individual record plates having printing characters, 105 feed means for moving the record plates *seriatim* and step by step along the runway to and past the impression point, selector means on the record plates indicating numbers, number wheels, and mechanism for automatically operating said number wheels, 110 said mechanism being controlled by the selector means, substantially as described.

9. In combination impression means, a table having a straight runway, individual 115 record plates having printing characters and selector means indicating numbers or digits of numbers, means for feeding the plates along the runway step by step, number wheels, a contact head having members to 120 contact with the selector means on the record plate, and means controlled by the said contacts for actuating the number wheels in accordance with the values represented by the selector means with which contact is 125 made, substantially as described.

10. In combination an impression head, individual record plates bearing printing characters and selector devices a contact head having movable contact devices to be 130

set by engagement with said selector devices, digit wheels, actuators for said digit wheels, means for setting the actuators up against the contact devices as adjusted into 5 stopping position by engagement with the selector devices, and means for returning the actuators to normal position to thereby transfer the values onto the digit wheels.

11. In combination impression means, individual record plates, bearing printing characters and selector devices, a contact head having movable members to engage the selector devices and be set thereby, said members acting as circuit closers and as 10 stops, number wheels, actuators therefor to be arrested in set-up position by said stops, electro-magnetic means for operating the said actuators, said electro-magnetic means being controlled by a circuit made by engagement of the movable members of the 15 contact head with the selector devices on the plates, and means for restoring the actuators to normal position to thereby transfer the values onto the number wheels, substantially as described.

12. In combination an impression head, a table, a plate feeder for moving printing plates along said table, an oscillating arm, a member mounted coaxially with the arm, a 20 pawl shiftable on the arm and when in one position engaging the said member to move the same, a connection between said member

and the impression head to move the latter when the pawl is in engagement with said member, and a member to set the pawl and 35 detector connections extending to the printing plate for controlling the last mentioned member, substantially as described.

13. In combination an impression head, a table having a runway for printing plates, a 40 rocking lever consisting of two arms coaxially mounted, a connection for operating one of the arms, toggle link connections between the arms, connections leading from one of the arms for feeding the printing 45 plates, a rocking member coaxially mounted with the arm of the lever, a connection between said rocking member and the impression head, a shifting pawl on one of the arms for operating said rocking member, and detector means coöperating with the printing plates for controlling the shifting pawl, the said toggle link connection between the arms allowing one of the arms to yield in respect to the other to eliminate the plate feeding 50 function should a plate become jammed in the runway, substantially as described.

In testimony whereof, I affix my signature in presence of two witnesses.

FREDERICK C. DOLCATER.
